UNITED STATES PATENT OFFICE.

ALEXANDER LESLIE, OF WALKERVILLE, CANADA, ASSIGNOR OF ONE-HALF TO GEORGE E. TITCOMB, OF PHILADELPHIA, PENNSYLVANIA.

VESSEL.

No. 821,514.

Specification of Letters Patent.

Patented May 22, 1906.

Application filed December 7, 1904. Serial No. 285,863.

To all whom it may concern:

Be it known that I, ALEXANDER LESLIE, a subject of the King of Great Britain and Ireland, residing at Walkerville, Ontario, Canada, have invented certain Improvements in Vessels, of which the following is a specification.

The object of my invention is to so construct a vessel that cars can be run over the deck of the vessel and dumped directly into the hold or storage-space.

My invention is particularly adapted for loading vessels with coal or grain in bulk.

In the accompanying drawings, Figure 1 is a side view of my improved vessel. Fig. 2 is a plan view showing the track-sections thrown back, so as to leave the hatchways entirely open to allow for the insertion of a bucket. Fig. 3 is a plan view similar to Fig. 2 with the track-sections in position over the hatchways, so that cars can be run over the same. Fig. 4 is an enlarged transverse section on the line 4 4, Fig. 2. Fig. 5 is an enlarged transverse section on the line 5 5, Fig. 3. Fig. 6 is a perspective view of one of the pivoted track-sections, and Figs. 7 and 8 are views of modifications of the invention.

I have illustrated my invention in connection with a steamship A, having a pilot-house ³⁰ a at the bow and boiler and engine rooms a' on each side at the stern. It will be understood, however, that my invention can be applied to any type of boat without departing from the main feature of the invention.

B is the hold of the vessel, extending in the present instance from a point directly back of the pilot-house to a point directly in front of the engine-room, and the hold is the full width of the vessel, giving the vessel a large capacity for storage of material.

b b are the ordinary transverse deck-beams spaced sufficiently apart to allow for the passage of buckets for the removal of material from the hold. In vessels of this type it is the common practice to use what is termed a "clam-shell" bucket hung from a suitable crane-boom or overhead structure, the bucket being of such size as to readily pass between the transverse beams, so as to remove material from any portion of the hold.

In the present instance the engine-rooms a' are situated on each side of the vessel so as to allow a clear deck-space for the tracks D D,

which extend from the stern of the vessel, as shown in Figs. 2 and 3, to the edge of the hold, 55 so that the vessel can be placed stern on against the wharf in line with tracks on the wharf and the cars can be transferred from tracks on the wharf directly to tracks on the vessel. 60

E is a series of movable sections made up of beams E' and cross members and having rails e, which when in position as shown in Fig. 3 align with the rails of the tracks D D, so that the cars can be moved from the tracks 65 D onto the sections E directly above the hold of the vessel. These sections are made open, as shown in Figs. 3, 5, and 6, so that a car on the rails of the sections E can be discharged directly into the hold of the vessel. In the 70 present instance these sections E have arms e', which are pivoted at f to brackets F, secured to the deck of the vessel and so proportioned that when the sections E are thrown back, as in Fig. 4, the beams E' and rails e 75 are clear of the hold, so as to not interfere with the proper operation of the bucket when the material is to be removed from the hold of the vessel. It will be understood that the construction of these pivoted sections may be 80 modified considerably without departing from my invention and that the vessel may be provided with a single track D', as shown in Fig. 7, instead of a double track, or the rails e' e' may be mounted in suitable slide- 85 ways E', as shown in Fig. 8, instead of being pivoted, although I prefer the pivoted construction, as it allows for the ready adjustment of the parts and gives freedom for the movement of the removing-bucket. 90

When the vessel is to be loaded with coal, ore, or other material, it is placed in a dock, so that the permanent tracks D on the vessel will align with the tracks on the wharf. The frames E are placed in position, as shown 95 in Figs. 3 and 5, so that the tracks will align with the permanent tracks D. Then a train of cars is moved onto one or both of the tracks and their contents discharged by simply tripping the hopper-bottoms in the ordinary manner, allowing the material to drop from the cars directly into the hold of the vessel. When the cars are emptied, they are backed off the vessel again and other cars run on until the hold is filled. The frames 100 E remain in position over the hold of the vessel. 105

sel until it is desired to remove the cargo. When the vessel is *en route*, the hold is covered by any suitable covering, as shown by dotted lines in Fig. 5. When the vessel reaches its destination, the covering is removed and the frames E are turned back on their pivots, as shown in Figs. 2 and 4, leaving the entire width of the hold open. The vessel is then placed in position at the wharf, so that a clam-shell-bucket elevator can be used to remove the cargo from the hold, the bucket being so proportioned as to readily pass between the deck-beams, as mentioned above. After the cargo has been removed the frames E can be turned on their pivots, so as to rest upon the deck-beams, and the cover can be applied, or in the case of the vessel being used to convey other material to its original port the frames E can be moved clear for the placing of material in the hold where it is not desired to reload the vessel from cars direct.

I claim as my invention—

1. The combination of a vessel having a hold and having a series of transverse deck-beams with longitudinal rails mounted on said beams and extending to one end of the vessel, the space between the beams above the hold being open for the passage of a bucket for removing material from the hold, substantially as described.

2. The combination of a vessel having a hold with a movable track extending over the hold and alining with a track on the deck of the vessel, said hold being open, when the track is moved, for the passage of

a bucket for removing material from the hold, substantially as described.

3. The combination of a vessel having a hold for the storage of material, fixed tracks on the deck of the vessel, pivoted frames on which are mounted the movable tracks which aline with the fixed tracks of the vessel, said movable tracks, when in line with the fixed tracks, extending over the hold of the vessel, substantially as described.

4. The combination of a vessel having a hold for the storage of material, two fixed tracks extending from one end of the vessel to the hold, two series of movable tracks pivoted to the deck of the vessel and arranged to either swing over the hold and in alinement with the fixed tracks, or to be thrown back clear of the hold and out of alinement with the fixed tracks, substantially as described.

5. The combination of a vessel having a hold, transverse deck-beams extending across the hold, pivoted frames having tracks thereon, said frames being pivoted to brackets on the deck of the vessel and arranged, when in alinement with the fixed tracks on the vessel, to rest upon the deck-beams, and, when thrown back, to be clear of the hold, substantially as described.

In testimony whereof I have signed my name to this specification in the presence of two subscribing witnesses.

ALEXANDER LESLIE.
